UNITED STATES PATENT OFFICE.

CLARENCE A. HILL, OF COLUMBUS, OHIO, ASSIGNOR TO THE CHAMPION KEROSENE-BURNER COMPANY, OF KENTON, OHIO, A CORPORATION OF OHIO.

KEROSENE-GAS-BURNING FURNACE.

1,352,063.

Specification of Letters Patent. Patented Sept. 7, 1920.

Application filed November 7, 1919. Serial No. 336,376.

To all whom it may concern:

Be it known that I, CLARENCE A. HILL, a citizen of the United States, residing at Columbus, in the county of Franklin and State of Ohio, have invented certain new and useful Improvements in Kerosene-Gas-Burning Furnaces; and I hereby declare that the following is a full, clear, and exact description thereof, reference being had to the accompanying drawings, which form part of this specification.

This invention relates to kerosene gas generators and burning furnaces of the type disclosed in the application of Louis F. Bertrau, (Case 6326), filed May 2, 1919, Serial No. 294,274, and my application (Case 6370), filed October 11, 1919, Serial No. 330,061.

The objects of the present invention are to prevent back fire in the mixing tube of the generator by conduction of heat from the furnace; and to improve and simplify the connection between the mixing tube of the generator and the furnace. It has been found in operating furnaces constructed as illustrated in the aforesaid applications, that when such a furnace is operated for a long period of time the heat in the furnace is gradually conducted back through the supply pipe to the mixing tube, and in time the mixing tube becomes so hot as to actually ignite the gaseous mixture in this tube, thus causing back-fire therein and requiring temporary stopping of the furnace.

I have found after many attempts to overcome this trouble, and by a long series of tests, that by protecting the inlet tube to the furnace and the elbow connecting such tube with the supply pipe leading to the mixing tube, this objectionable back-firing can be effectively prevented, even when the furnace is operated continuously for many hours.

In the accompanying drawings I have illustrated a practical embodiment of the invention and will describe the same with reference thereto, and then set forth in the claims the essentials of the invention and novel features and constructions, for all of which protection is desired.

In said drawings:

Figure 1 is a side elevation of a furnace with a generator such as is shown in my aforesaid application, connected therewith, and provided with novel means for prevent-

ing overheating of and back-firing in the mixing tube by reason of the heat generated in the furnace.

Fig. 2 is an enlarged vertical section showing the connection between the mixing tube 60 and the furnace, and the heat insulating means.

Fig. 3 is a plan view of the cup shown in Figs. 1 and 2.

Fig. 4 is a top plan view of Fig. 3.

Fig. 5 is a top plan view of a modified construction of cup used where the heated gases are to be introduced horizontally instead of vertically into a furnace.

Fig. 6 is a part side elevation and part section of Fig. 5, showing the cup in elevation.

The furnace 5 (Fig. 1) may be constructed substantially as shown and described in the aforesaid applications; and connected therewith is a hydro-carbon gas generating apparatus, such as described in my aforesaid application, comprising in brief a generating coil 1, surrounding a back pressure gas chamber 2, and protected by a hood G; the generating coil being connected to a fuel supply pipe 1^a at its lower end, and to a jet head 1' at its upper end; said jet head discharges into a mixing tube 4, which has a lateral connection 4^b with the inlet 2^a of the chamber 2; and said mixing tube is connected by a pipe 4^x, and elbow 4^c, to a pipe 4^d, which enters the furnace 5, as described in the aforesaid applications. The furnace 5 is preferably provided with an outer metallic casing 5^e, and is interiorly lined with fire clay, asbestos cement, or other highly refractory and preferably non heat conducting material, indicated at 5^b. The aforesaid parts are or may be all constructed substantially as described in the aforesaid applications and are not specifically claimed herein.

As stated the heat in the furnace chamber 5^a is so great that in such a furnace as heretofore constructed, when the furnace is operated the heat is eventually transmitted from the pipe 4^d to elbow 4^c and back through the pipe 4^x to the mixing tube 4, which eventually becomes so hot as to be apt to ignite the mixture therein, causing back-firing and necessitating temporary stoppage of the furnace and restarting thereof.

In the present invention I prevent such back-firing by providing, at the upper outer

end of the opening for pipe 4^a in the wall of the furnace, a chamber or recess 6; and exterior to this chamber an opening is cut in the metal jacket 5^c; and around this opening is fitted a hollow member or cup 7, which is of much larger diameter than the pipe 4^x, or 4^a, and is sufficiently large to surround the elbow 4^e, which is spaced on all sides from the walls of the cup. The cup 10 may have a flange 7^a, to fit against the outer surface of the casing 5^c, and be provided with perforated lugs 7^e for the passage of retaining bolts or rivets by which the cup may be fastened to the casing 5^c. The cup 15 has a collar 7^b on its inner end to fit the opening in the casing 5^c.

The interior of this cup forms a continuation of the chamber 6 and the cup and chamber are filled with a packing 8 of any suitable non heat conducting material, which 20 packing surrounds the upper end of the pipe 4^a, the elbow 4^e, and the end of pipe 4^x connected therewith.

The cup 7 preferably has a vertical slot 7^e 25 in one side to permit the ready positioning of the pipe 4^x, elbow, and pipe 4^a after the cup has been attached to the casing; or to permit the pipes and elbow to be detached from the furnace, if desired, without having 30 to detach the cup.

It will be seen by reference to the drawings that the elbow 4^e and the connected threaded ends of the pipes 4^a and 4^x are entirely surrounded by the non heat conducting packing and I have found by severe tests 35 that with this construction the transmission of heat from the furnace chamber 5^a back to the mixing tube 4 is so effectually checked that the furnace can be operated indefinitely 40 at full capacity without any back-firing resulting from overheating of the pipe 4^x, or the mixing tube.

If it is desired to introduce the pipe 4^a horizontally into the furnace 5, the construction 45 shown in Figs. 5 and 6 may be used. In this case the cup 9 substantially conforms to the cup already described, and is open at top but closed at bottom, and has an opening at one side and adjacent this opening a 50 flange 9^a provided with perforated lugs 9^e for the passage of securing bolts or rivets. The cup 9 as shown also has an inner collar 9^b engaging the opening in the side of the casing 5^c. The chamber 6 is formed in the 55 side wall of the furnace, and connects with the interior of the cup as described. The cup 9 also has a slot 9^e in one side for the entry of the pipe 4^x, the elbow 4^e being contained within the cup, and the pipe elbow 60 and the connections to the pipe ends thereof are insulated from the cup and protected by a packing 8 of non heat conducting material, as described.

I do not consider the invention restricted 65 to the specific cups shown, and these may be

modified to suit the particular application and mode of introduction of pipe 4^a into the furnace.

What I claim is:

1. In combination, a furnace having an 70 opening in its wall for the reception of a fuel gas supply pipe; a hydrocarbon gas generator having a mixing tube, and a supply pipe for conducting the mixture from this tube having an elbow and extending into 75 the furnace through said opening; with a cup connected to the furnace and surrounding said opening and inclosing the elbow, and a non heat conducting packing within this cup around such elbow, substantially as 80 described.

2. In combination, a furnace having an 85 opening in its wall for the entry of a fuel gas supply pipe and an enlarged chamber at the outer end of said opening; a hydro- 90 carbon gas generator having a mixing tube, and a pipe connected with said tube having an elbow and extending into the furnace to conduct the mixture thereinto; with a cup connected to the furnace and surrounding the elbow; and a non heat conducting packing within this cup inclosing such elbow, substantially as described.

3. The combination of a furnace having 95 an opening in its wall for the reception of a fuel gas supply pipe; and a hydro-carbon gas generator having a mixing tube, a pipe for conducting the mixture from this tube, an elbow connected with this pipe, and a supply pipe connected with the elbow extending 100 into the furnace through said opening; with a cup connected to the furnace and surrounding said opening and inclosing the elbow and the threaded ends of the pipes connected therewith; and a non heat conducting packing within this cup around such 105 elbow and the ends of the pipe connected therewith, substantially as described.

4. The combination of a furnace having 110 an opening in its wall for the entry of a fuel gas supply pipe; and an enlarged chamber at the outer end of said opening; and a hydro-carbon gas generator having a mixing tube, a pipe for conducting the mixture from this tube, an elbow connected with this pipe, 115 and a pipe connected with the elbow extending into the furnace to conduct the mixture thereinto; with a cup connected to the furnace and surrounding the elbow and the threaded ends of the pipes connected therewith, and non heat conducting packing within this cup inclosing such elbow and the threaded ends of the pipe connected therewith, substantially as described.

5. In combination, a furnace having an 125 opening in its wall for the reception of a fuel gas supply pipe; a hydrocarbon gas generator having a mixing tube, and a supply pipe for conducting the mixture from this tube having an elbow and extending into 130

- the furnace through said opening; with a cup connected to the furnace and surrounding said opening and inclosing the elbow, said cup having a slot in its side for the accommodation of the said pipe and an opening communicating with the opening in the wall of the furnace; and a non heat conducting packing within this cup around such elbow, substantially as described.
- 5 6. In combination, a furnace having an opening in its wall for the entry of a fuel gas supply pipe and an enlarged chamber at the outer end of said opening; and a hydro-carbon gas generator having a mixing
- 15 tube, and a pipe connected with said tube having an elbow and extending into the furnace to conduct the mixture thereinto; with a cup connected to the furnace and surrounding the elbow, said cup having a slot in its side for the accommodation of the said conducting pipe and an opening communicating with the chamber at the outer end of said opening, and a non heat conducting packing within this cup inclosing such elbow, substantially as described.
- 20 25
- In testimony that I claim the foregoing as my own, I affix my signature.

CLARENCE A. HILL.
